UNITED STATES PATENT OFFICE.

CARL R. SHAFER, OF DETROIT, MICHIGAN.

HAIR-CUTTING GAGE.

1,390,465.

Specification of Letters Patent. Patented Sept. 13, 1921.

Application filed February 2, 1921. Serial No. 441,750.

To all whom it may concern:

Be it known that I, CARL R. SHAFER, a citizen of the United States, residing at Detroit, in the county of Wayne and State of Michigan, have invented certain new and useful Improvements in Hair-Cutting Gages, of which the following is a specification.

This invention relates to hair-cutting gages. It is the object of the invention to provide a hair-cutting gage that can be utilized by a barber to guide him in cutting hair.

In the drawings,—

Figure 1 is a side elevation of the gage attached to the head.

Fig. 2 is a front elevation taken at a 90 degree angle from the view shown in Fig. 1.

Fig. 3 is a section taken on the line 3—3 of Fig. 2.

Fig. 4 is a view of a simpler modified form of my invention.

a represents a plate which is adapted to fit a person's forehead. This plate is provided with a curved slot *b* having several offsets *c*. This forward plate *a* is connected by elastic straps *d* with the rear plate *e* which is provided with one long slot *f*. The yoke *g* is preferably a two-part yoke by reason of the set screw clamp *h* slidable along the larger rod. The smaller rod *j* is slidable through the set screw clamp *k*. The lower end of the larger rod *g* is also slidable through a clamp *l*. Obviously the yoke may be adjusted up and down in the two clamps *k* and *l* and the parts of the yoke may be adjusted with respect to each other by the clamp *h*. This permits the fitting of the gage to the various heads met with in barber practice regardless of their eccentricities. Furthermore, by adjusting the yoke up and down in the clamps *k* and *l* and *h* the length of the cut of the hair may be adjusted to suit.

The operation is as follows: Before the gage is applied to the head the barber will clip or shear the sides of the head up to the dotted line *s*—*s* (Fig. 1). Whether clipping or shearing is done, is, of course, largely a matter of taste of the patron. The barber then applies the gage to the head, as shown in Fig. 2, for instance. He takes his position behind the person, combs the hair to a perpendicular position, and the shears, rested against the back of the gage, are then manipulated to cut off the hair held in the comb. The operation proceeds upwardly to

the point *t*. Thereupon the gage is shifted along to about a central position on the head. The operator then repeats the operation up to the point *t* as before. The gage is then moved to the extreme left position and the operation repeated until the entire back part of the head is completed. The operator then takes a position in front of the patron and finishes the top of the head by moving the shears along the gage from front to back, combing the hair up perpendicularly as before. The gage is shifted the same way along the slots to cover the entire head until the hair on the entire head has been cut.

It will be apparent that the slots *b* and *f* make possible moving the gage from side to side of the head. Furthermore, the auxiliary slots *c* in the plate *a* permit the gage to be set at any intermediate point along the length of the plate *a*. These auxiliary slots *c* make possible any angular adjustment, as shown by the dotted lines, to accommodate any shape head.

It will be seen that in the clamp *k* the set screw *v* bears against the rod part *j*. This rod part *j* runs through an elongated hole *w* in the clamp body. Consequently the end of the set screw *v* jams the rod part *j* up against the washer *r* and thereby tightly binds the clamp to the plate *a* in any desired position. It will also be noted that the plate *a* is bossed or pressed out, as shown in Fig. 3, for the purpose of providing clearance to accommodate the head *q* of the clamp body. Felt strips *x* are provided at the top and bottom and back of the plate to relieve the harshness of the plate upon the forehead.

In place of using a yoke supported upon the head by plates connected by elastic straps, the yoke may be constructed of a single piece of spring rod *n*, as shown in Fig. 4, and provided with a pair of pads *o* and *p* to press in the front and back of the head and thereby hold the yoke in place. The shearing operation will be precisely the same and the yoke may be moved about on the head in much the same manner as already indicated.

What I claim is:

1. A hair-cutting gage, having in combination, a yoke for bridging the head in spaced relation therewith to form a guide for the shears, and means for supporting the yoke upon the head.

2. In a hair-cutting gage, a rod-like yoke shaped intermediate its ends to bridge the

105

110

head in spaced relation thereto and form a guide for the shears that are contacted on the yoke and provided at its ends with means by which the same is supported upon the head.

3. In a hair-cutting gage, the combination of a pair of plates for engagement with the front and back of the head, elastic straps connecting the said plates, and a yoke supported by the said plates in spaced relation with the head for guiding the shears of the operator.

4. In a hair-cutting gage, the combination of a pair of plates forming front and back plates for engagement with the head, a yoke adjustably supported within said plates and which can be moved up and down with respect to the head by reason of its being adjustably supported within said plates, and straps connecting the plates together.

5. In a hair-cutting gage, the combination of a pair of plates, one adapted to fit the forehead of the head, the other the back of the head, a clamp on each plate, and a rod-like yoke adjustably supported within the said clamps of the plates and removably

away or toward the crown of the head, and straps connecting the plates together.

6. In a hair-cutting gage, a pair of plates, one to be secured to the front of the head, the other to the back of the head, a pair of straps connecting the same, and a yoke adjustably secured in said plates and comprising two rod portions adjustably clamped together.

7. In a hair-cutting gage, the combination of a pair of plates, one fitted to the front of the head, the other to the back of the head, a pair of straps connecting the same, a yoke supported upon said plates and movable transversely of the head by its ends being adjustable along the plates.

8. In a hair-cutting gage, the combination of a pair of plates, one to fit the front of the head, the other the back of the head, a pair of straps connecting the plates, and a clamp on each plate for supporting the yoke ends, each of the clamps being movable along the plate to move the yoke transversely of the head.

In testimony whereof I affix my signature.
CARL R. SHAFER.
